(57) **CLAIM**

The ornamental design for a waffle maker, as shown and described.

DESCRIPTION

FIG. 1 is a perspective view of a waffle maker showing my new design, in accordance with a first embodiment of the present invention.

FIG. 2 is a front elevational view thereof.

FIG. 3 is a rear elevational view thereof.

FIG. 4 is a right-side elevational view thereof, the left-side elevational view being the mirror image thereof.

FIG. 5 is a top plan view thereof.

FIG. 6 is a perspective view of a waffle maker showing my new design, in accordance with a second embodiment of the present invention.

FIG. 7 is a front elevational view of the waffle maker of FIG. 6.

FIG. 8 is a rear elevational view of the waffle maker of FIG. 6.

FIG. 9 is a right-side elevational view of the waffle maker of FIG. 6, the left-side elevational view being the mirror image thereof.

FIG. 10 is a top plan view of the waffle maker of FIG. 6.

FIG. 11 is a perspective view of a waffle maker showing my new design, in accordance with a third embodiment of the present invention.

FIG. 12 is a front elevational view of the waffle maker of FIG. 11.

FIG. 13 is a rear elevational view of the waffle maker of FIG. 11.

FIG. 14 is a right-side elevational view of the waffle maker of FIG. 11, the left-side elevational view being the mirror image thereof; and,

FIG. 15 is a top plan view of the waffle maker of FIG. 11.

The broken lines showing a handle and control knobs on a control panel are for illustrative purposes only and form no part of the claimed design.
